PROCESS FOR TREATING HYDROCARBON
OILWalter A. Schulze, Bartlesville, Okla., assignor to
Phillips Petroleum Company, a corporation of
DelawareNo Drawing. Application May 11, 1937,
Serial No. 142,018

6 Claims. (Cl. 196—30)

This invention relates to improvements in processes for sweetening sour hydrocarbon oils with solutions of copper salts, and more particularly to a method of removing traces of copper-containing reaction products from oils having been 5 so treated.

When sour hydrocarbon oils are treated with copper solutions, e. g., the solutions described in U. S. Patent 1,964,219, the mercaptans are converted to disulfides. The reactions may be expressed by the following equations:

Mérap- Cupric
tan chlorideCuprous Cupric
mercaptide chlorideIt is noted that in the first stage of the reaction one-half of the mercaptans are converted to disulfides and the other half to cuprous mercaptide. Then in the second stage of the reaction the cuprous mercaptide is oxidized to the disulfide form. Therefore, when the reaction is 100 per cent completed all of the mercaptans will have been converted in disulfides and there will be no cuprous mercaptide left dissolved in the gasoline. Such a condition, however, is seldom attained in commercial plant operation. In such operation the sour gasoline is intimately contacted with the copper solution in a centrifugal pump or by some means for an extremely short period of time—longer contacting with aqueous solutions would be economically impractical. The treated gasoline will be negative to the so-called doctor test and for all practical purposes is sweet, but nevertheless it will contain in solution a small amount of the intermediate reaction product, cuprous mercaptide.

The amount of the cuprous mercaptides left dissolved in the gasoline will depend on many factors, such as the type of gasoline, the oxidation potential of the solution, the intimacy of contact of the copper solution with the gasoline, the presence or absence of particularly refractory mercaptans, etc. In general, however, the soluble copper compounds left in the gasoline sweetened by plant methods will be present to the extent of 0.001 to 0.00001 per cent copper. While these quantities are extremely low, they are more than sufficient as deleterious oxidation catalysts. In the presence of dissolved copper mercaptides or other copper-containing compounds, which are potent oxidation catalysts, many gasolines have a tendency to be unstable with respect to formation of color and gum, or if they are not subject

to instability in themselves, they may produce these effects when blended with other gasolines which are more susceptible to oxidation. For example, a straight-run gasoline consisting principally of saturated hydrocarbons may be entirely 5 stable even though it contains appreciable quantities of copper-containing impurities, but will cause instability in the resulting blend when mixed with a copper-free and relatively stable cracked gasoline.

Since most motor fuels are marketed as a blend of two or more base gasolines, it is desirable that each component be free of copper, regardless of whether or not it is stable by itself. As an adjunct to the copper sweetening process 15 it is, therefore, necessary to follow the sweetening step with a secondary treatment designed to remove any traces of copper compounds which are present in the treated oil.

As stated above it should be understood that 20 the concentration of these impurities is so minute that they cannot usually be detected by ordinary analytical means, and it may be days or weeks before their presence is detected by effect. Special analytical tests have had to be devised 25 for the quantitative determinations mentioned herein. A deleterious concentration of copper mercaptide may be present even when the oil displays the characteristic negative concentration to the standard, doctor test, and this test 30 therefore cannot be depended on as a criterion of the presence or absence of mercaptides. Relatively large amounts of mercaptides, however, will generally give a delayed positive reaction to the doctor test, i. e., the positive reaction is discernible only after a period of from several 35 minutes to several hours after the sample has been contacted with the doctor test solution and sulfur, the period of delay depending mainly on the concentration of mercaptide present.

I have found that a more sensitive and reliable test involves acceleration of color formation in the presence of copper by addition of benzoyl peroxide to the sample, or if the sample is a 45 relatively stable oil to a mixture of the sample and an oil known to be susceptible to oxidation and free of copper. One way of making this test consists in adding 10 mg. of benzoyl peroxide, dissolved in 1 ml. of benzene, to (a) 100 ml. of the sample, and (b) a second 100 ml. of the sample 50 after washing it with a sodium sulfide solution to remove any traces of copper present. Discoloration of portion (a) in comparison to the blank (b) after the two have stood in the dark 55 for from one to four hours indicates the presence of copper. A copper concentration as low as 0.00001 per cent in gasoline may be easily detected.

It is an object of the present invention to sta- 60

bilize petroleum oil which has been treated with a copper sweetening reagent.

It is a further object of this invention to stabilize petroleum oil which has been treated by a copper reagent against catalytic deterioration.

A still further and more specific object of this present invention is the removal of relatively small amounts of copper-containing reaction products from petroleum oils which have been treated previously with copper sweetening reagents.

Other objects and advantages of the present invention will be apparent from the following detailed description of the invention.

15 Applicant has now found that the aforementioned copper mercaptides which are left in oil that has been treated with copper solutions may be rapidly and completely removed by subjecting the oil to a secondary treatment with a concentrated solution containing cupric and chloride ions adsorbed on a solid adsorbent carrier material. The reaction appears to be as follows:

25 The reagent for the secondary treatment may be prepared by impregnating such solid adsorbent materials as fuller's earth (preferred), charcoal, silica gel, alumina, etc., with concentrated aqueous solutions of copper chloride, or of copper sulfate or other copper salts, and sodium chloride or other alkali chlorides. To secure even distribution of the solution on the adsorbent, relatively dilute solutions may be applied to the adsorbent and subsequently concentrated as desired by removal of a portion of the water of solution.

30 This secondary or stabilizing treatment of the oil with the above described reagent consists in 40 contacting it in liquid phase in a manner similar to filtration, at flow rates preferably within the range of from 1 to 10 volumes of oil per hour per volume of reagent, at substantially atmospheric temperatures, preferably 60 to 100° F., and nominal pressures.

35 As one example of the operation of this invention, a straight run gasoline from West Texas crude was sweetened with a copper solution containing approximately 15 per cent $\text{CuSO}_4 \cdot 5\text{H}_2\text{O}$ 50 and 15 per cent NaCl , having an oxidation potential within the range of 380 to 440 millivolts and pH 2.8. After this treatment it contained copper mercaptides varying within the range of 0.0002 to 0.0001 per cent copper, and always showed 55 strongly positive on the benzoyl peroxide test. This gasoline was filtered through a stabilizing reagent prepared by impregnating 15-30 mesh fuller's earth with a solution of copper sulfate and sodium chloride. The stabilizing reagent 60 contained approximately 3 per cent copper, 5 per cent chloride, and 15 per cent water. The sweetened oil was filtered through the reagent at rates of 2 to 5 volumes per hour. No air was added to the gasoline during either the sweetening 65 or the stabilizing step. Over an extended period of operation during which more than 2000 volumes of sweetened oil were treated, the finished gasoline was completely free of copper as evidenced by the extremely sensitive "benzoyl peroxide" test described above. Furthermore, there was no noticeable depreciation in the activity 70 of the stabilizing reagent after the treatment of 2000 volumes of gasoline and its life is undoubtedly very long.

When using fuller's earth without the adsorbed copper and chloride solution, it was noted that the copper mercaptides were extracted from the first several volumes of gasoline by adsorption on the earth but that the earth quickly became saturated with the mercaptides and became inactive. As explained above, the copper solution adsorbed on the fuller's earth (as a carrier body) oxidizes the cuprous mercaptides to disulfides and thereby makes the sweetening reaction 100 per cent complete. Fuller's earth alone cannot do this.

5 It is evident from the foregoing that applicant has discovered and disclosed a new method of stabilizing copper reagent treated oils which constitutes an important technical step forward in the art.

15 Having thus described the present invention, what is claimed is:

1. In the process of sweetening oils with solutions of copper salts in which the copper salt solution is intimately admixed with the oil, the step of removing copper mercaptides from the sweetened oil by contacting said oil in the absence of air with a solid adsorbent material impregnated 20 with a solution of cupric and chloride ions.

2. The method of stabilizing petroleum oil which has been treated with a solution of a copper sweetening reagent, which comprises passing said treated oil in liquid phase in the absence of 30 air through a filter bed of treating agent consisting of adsorbent carrier material impregnated with an aqueous solution yielding cupric and chloride ions, whereby the oil is freed of copper-containing compounds and stabilized against catalytic deterioration, and separating the stabilized oil from the treating agent.

3. The method of stabilizing petroleum oil which has been sweetened with copper solution which comprises passing the sweetened oil in the 40 absence of air through a filter bed of solid adsorbent material impregnated with a concentrated aqueous solution of copper sulfate and an excess of sodium chloride.

4. In the process of sweetening petroleum oil with copper solutions, the step of subjecting the sweetened oil in the absence of air to the action of a solid adsorbent material impregnated with a solution containing cupric ions and chloride ions, whereby copper-containing impurities are removed.

5. In the process of sweetening petroleum oil with copper solutions, the step of removing copper-containing impurities from the sweetened oil by subjecting said oil in the absence of air to the action of a solid adsorbent material impregnated with a solution containing cupric ions and chloride ions.

6. A process for treating petroleum oil containing mercaptans, which comprises intimately contacting said oil with an aqueous solution containing cupric ions and chloride ions to sweeten the hydrocarbon oil, and subsequently passing said sweetened oil in the absence of added free oxygen-containing gas over a treating agent consisting of adsorbent carrier material impregnated with an aqueous solution yielding cupric and chloride ions, whereby the oil is freed of copper-containing compounds resulting from the first mentioned treatment and stabilized against catalytic deterioration, and separating the stabilized oil from the treating agent.
